The ornamental design for a toy sword, as shown and described.

DESCRIPTION

FIG. 1 is a front, top perspective view of a toy sword embodying my new design;

FIG. 2 is a rear, bottom perspective view thereof;

FIG. 3 is a front view thereof;

FIG. 4 is a side view thereof as seen from the left-hand side of FIG. 3;

FIG. 5 is a top view thereof;

FIG. 6 is a bottom view thereof;

FIG. 7 is a side view thereof as seen from the right-hand side of FIG. 3; and,

FIG. 8 is a rear view thereof.

The broken lines shown in FIGS. 1, 3, 4 and 7 form no part of the claimed design.

1 Claim, 4 Drawing Sheets(56)
